X-RAY TUBE

Original Filed Oct. 18, 1923

UNITED STATES PATENT OFFICE

MONTFORD MORRISON, OF CHICAGO, ILLINOIS, ASSIGNOR, BY MESNE ASSIGNMENTS, TO
WESTINGHOUSE LAMP COMPANY, A CORPORATION OF PENNSYLVANIA

X-RAY TUBE

Original application filed October 18, 1923, Serial No. 669,315. Divided and this application filed January 4, 1924. Serial No. 684,336.

This application is a division of my co-pending application, Serial No. 669,315, filed October 18, 1923, transformers and transformer devices.

This invention relates to evacuated devices and more particularly to X-ray tubes and related devices.

An object of my invention is the provision of X-ray tubes especially adapted for small dental outfits using high voltage.

Another object of my invention is the provision of an X-ray tube adapted to be insulated by electrostatic field control and cooled by means of air, without the necessity of employing oil for such purposes.

A further object of my invention is the provision of an X-ray tube adapted to be operated on high voltage and designed to be insulated by electrostatic field control and cooled by air, whereby lightness in weight is attained.

A still further object of my invention is the provision of an X-ray tube in which an electron-stream is thermonionically generated and flows to the anode or target, substantially along the longitudinal axis of the tube and the main beam of X-rays generated flows back along the same axis, through the center of the electron source and out of the tube.

Other objects and advantages of the invention will become apparent as the description proceeds.

X-ray apparatus, especially adapted for dental use, have been constructed in which a high voltage transformer and the X-ray tube are both contained in a small oil-filled tank which is suspended on a wall bracket. The entire outfit is made small enough to be readily placed in various positions necessary for dental X-ray work.

This type of construction entirely obviates any high tension leads, since all high voltage conductors are contained in a small tank. The disadvantage of such a construction lies in the fact that the tank is filled with oil and it is, therefore, more or less troublesome to replace damaged tubes and more or less dangerous if such a tube breaks while in service.

In my copending application, Serial No.

669,315, filed October 18, 1923, transformer and transformer devices, I have disclosed an outfit of such a type in which the use of oil for insulation and cooling of the X-ray tube is dispensed with and the tube is, instead, insulated by electrostatic field control and cooled by air with the result that it is somewhat lighter in weight than such an oil-cooled outfit and because of my special design, is also about the same size.

The present application, which is a division of said copending application, is concerned with the X-ray tube, particularly adapted for use with such a dental outfit, although it is obvious that it is not restricted to such use but may be employed in any way desired.

A preferred embodiment of my novel form of X-ray tube may comprise an evacuated envelope formed with a main substantially spheroidal portion and an auxiliary substantial cylindrical extension therefrom. This extension preferably holds the anode or target of the X-ray tube and is preferably provided with a screw-plug electrically connected to said target, so that the tube may be conveniently connected and disconnected from any auxiliary apparatus, such as a high voltage transformer, with which it is to be used.

When in operation, the tube is preferably supported by said anode screw-plug and the axis of said tube and anode is preferably normally approximately vertical with the anode extending downwardly toward the main substantially-spheroidal portion of the tube from said anode extension, but it will be appreciated that the tube may be used in any position whatever and in the parent application, means have been provided for such positioning of the tube. The anode is preferably provided with a convex or substantially hemispheroidal end, the tip or working face thereof being formed of some refractory metal of high atomic weight, such as thorium, for example.

Extending from the opposite end of the tube, there is preferably a filamentary cathode adapted to be heated to an electron-emitting temperature by a pair of leading-in conductors extending through the main por-

tion of the tube envelope. The conductors are formed heavy enough to support said filamentary cathode and a focusing device surrounding the same.

5 My invention will better be understood by referring to the accompanying drawing, in which the single figure illustrates a preferred form of my X-ray tube, shown partly in section and illustrated diagrammatically as being connected to a suitable source of electrical energy and suitable transformers for the operation thereof.

10 In my copending application before referred to, of which this case is a division, I have described and claimed a preferred form 15 of transformer and casing therefor to be used as part of a dental X-ray outfit. This application is concerned primarily with the X-ray tube for such an outfit and I have, 20 therefore, only illustrated said tube in detail and the associated apparatus is illustrated diagrammatically.

It is obvious that my tube is not restricted 25 for use with dental outfits, but may be used for any purpose, especially where the space for the installation of such a tube is more or less limited, and where the practicability or convenience of such an outfit is advantageous or desirable.

30 Referring to the drawing, a preferred form of envelope for my X-ray tube is represented at 1, the said envelope being preferably constructed with a main substantially spheroidal portion 2 and an auxiliary substantially cylindrical extension therefrom at 3. The cylindrical extension is preferably provided with a screw-plug 4 adapted to be inserted in a receptacle or socket 5, similar to those in which ordinary incandescent electric lamps 35 are operated. Such a receptacle may form part of a casing and enclosed transformer 40 used in connection with my X-ray tube.

45 My X-ray tube 1 is novel in construction and related to several of my copending applications, specifically referred to in my aforementioned application. It is substantially symmetrical in design about its longitudinal axis, which is preferably in a generally upright position, when in normal operation, 50 with the extension 3 extending in an upward direction therefrom. Although such a position may be considered as a normal operating position, it is obvious that when my tube is employed as part of a dental outfit, means are 55 preferably provided whereby the same may be moved, as part of said outfit, to any desired position, so as to be conveniently utilized for directing the X-rays generated in a desired path.

60 Into said extension 3 is preferably sealed an anode or target 6 formed of good heat conducting material, such as copper, and having a substantially spheroidal or convex end 7. Into this end is preferably set a convex 65 tip or working face 8, which is preferably con-

structed of highly refractory metal of high atomic weight, such as thorium or the like. The opposite end of the anode is fixed at 9 to the extension 3 of the glass envelope 1 and electrically connected to the screw-plug 4, which is adapted to be screwed into the receptacle 5 forming the principal supporting means for fixing the position of the tube.

70 A focusing device 11, having a generally spheroidal and toroidal geometrical construction and a conspicuous absence of points and edges, where said points and edges would influence the electrical field distribution without the focusing device, is preferably employed. The focusing device is provided with a substantially central opening 12 permitting a conically divergent beam of X-rays to pass therethrough and cover the volumetric space represented by the angle 13. The opening in the focusing device and through which the divergent X-rays pass, therefore, serves simultaneously as a diaphragming device.

75 The focusing device 11 is preferably fixed in position by a plurality of rods or the like 14 and 15, sealed into glass or insulating parts 16 and 17, as is common in the manufacture 80 of evacuated devices, such as lamps. Into glass part 16 is pressed a leading-in conductor 18 which is formed into one or more convolutions, or connected to a filamentary cathode 90 formed into one or more convolutions, at 19. A cathode 19, substantially circular in plan, is illustrated in the drawing, although it is obvious that other forms, consisting of one or more convolutions, may be employed. The 95 said convolution or convolutions is or are of refractory metal adapted to be incandesced without substantial deterioration and are preferably constructed of thorium or other material of good electron-emitting properties, thereby adapting the cathode as a thermionic source of electrons. The other end of the electron-emitting portion 19 is connected to or continued as leading-in conductor 100 21, which is pressed into glass or insulating part 17 and serves as the remaining lead for the thermionic electron source.

105 Conductors 18 and 21 are sealed into the glass at 22 and 23 respectively. The ends of 110 said conductors are preferably supplied with contact buttons 24 and 25 respectively, which by means of corresponding contacts 26 and 27 respectively, and insulated lead wires 28 and 29 therefrom, serve as means for conducting 115 low voltage electrical current into the bulb of the X-ray tube and supplies heating current for the thermionic cathode 19. Lead wires 28 and 29 are preferably connected through switch 31 to the secondary 32 of a suitable heating transformer 33, the primary 120 of which is represented at 34. The conductor 28 may serve as a common connection for the low voltage winding of high voltage transformer, 35, and the thermionic filament 125 of the X-ray tube. Said high voltage trans-

former as shown, comprises primary winding 36 and secondary winding 37. The primary winding 36 is preferably connected through lead 38, switch 39 and common lead 28 to alternating current generator 41, or other suitable source of alternating current.

The secondary winding 37 of the high voltage transformer 35, is preferably connected to the anode 6 by lead 42 and to the cathode 10 by the common lead 28 through connection 43.

As the cathode end of the X-ray tube is preferably grounded, for example, at 44, it will be apparent that the only portion of the apparatus shown, at high voltage is the high 15 voltage transformer secondary winding 37, the anode 6 of the tube and the connection 42 therebetween. These portions of the apparatus are away from the patient and operator and may be securely enclosed and insulated, so as to avoid danger in using the device.

The focusing device 11 is preferably constructed of a refractory metal of high atomic weight, such as thorium or the like, and the 25 focal spot 8 on the anode 6 may so project into the spheroidal cavity of the said focusing device, as to substantially prevent the escape of X-rays from the said cavity, except through the opening 12 along the conical 30 space, represented at 13. In this way, my focusing device, which is preferably formed of material substantially opaque to X-rays, may serve as a shield against undesirable X-rays, though in some cases I may provide an 35 additional shield against undesirable X-rays in the form of a casing 45. In such a case, said casing is provided in the general neighborhood of 46, with a portion substantially transparent to desirable X-rays coming within 40 in the conical space 13, so that they may emerge into the useful X-ray field, such as that below 46.

The small parts, such 14, 15, 16, 17, 18, 19, 21, 22, 23 and the like are shielded electro- 45 statically by means of the focusing device 11, in such a way as to prevent said small parts from coming into the electrostatic field to any substantial degree and thereby influencing it. So it may be pointed out that 50 in viewing the X-ray tube in its casing, it will be noted that the outstanding characteristic is a substantial absence of points, edges and surfaces of small radii of curvature in the construction of parts used in locations 55 which influence the electrostatic field distribution caused by the high voltage employed in connection with my device, and I thereby not only improve the dielectric characteristics of the insulation properties utilized in my device, but I also improve the general operation of the X-ray tube itself.

It will be appreciated by those familiar with the art, that gaseous ionization within an X-ray tube may be dependent upon the maximum voltage stress within the rarefied gas

itself, and by giving such geometric construction of to the electrode and focusing member of my device as to reduce and equalize this aforesaid maximum stress, I not only improve the stability of the operation of the 70 X-ray tube, which is often affected by gaseous ionization, but also remove the necessity of utilizing such high vacua as has been thought necessary heretofore, to produce X-ray tubes which operate independent of troublesome gaseous ionization. 75

It will be appreciated that in all X-ray tubes, regardless of how much care is exercised in pumping out the residual gases, there is not only theoretically but practically in 80 every tube, appreciable gaseous ionization. This may be made evident by taking at random any hot-cathode tube of the art prior to my several inventions and with the filament cold impressing the maximum allowable potential upon the terminals of the tube and observing the phenomena which take place therewithin. Minute pale green fluorescent spots on the glass walls of said tubes will appear and upon investigation, 85 these spots will be found to be sources of X-rays produced by gaseous ions developed by the high dielectric field stresses caused by the sharp edges of the focusing device of the said tube, bearing irrefutable evidence of gaseous ionization. 90

By the employment of my surface-characteristic means, for controlling the electrostatic field distribution, such as for example, the spheroidal ended anode and the spheroidal toroidal focusing device, for reducing the dielectric field stresses about my electrodes, I find that I can produce a more dependable X-ray tube with less gaseous ionization present, than in the prior art tubes 100 and with higher gas pressures than possible without my improved electrodes, and further, with such pressures as have been common prior to the general use of thermionic 105 X-ray tubes. 110

Further, it will be appreciated that X-ray tubes which are dependent upon gaseous attenuation to reduce the gas ionization within the tube, are subject to instability and erratic behavior due to minute gas pressure 115 changes in the envelopes of said tubes. In these devices, pointed or edged electrodes do not have very pronounced working characteristics, and work more or less good or bad, depending upon the instantaneous value of the gas pressure within the tube. However, in my device, this characteristic is not strongly present, as more sharply defined critical points are found present during its 120 operation and phenomena due to gaseous ionization may be almost non-existent up to critical values, where it becomes more pronounced with greater rapidity. 125

It will be appreciated that with such a characteristic, so long as the critical point

has not been overstepped, gaseous ionization is conspicuously absent, and the X-ray tube may be operated with constantly changing and fluctuating gas pressures, without these changes or fluctuations being apparent in the operation or interfering with the stability of the X-ray tube.

The principal and essential elements of my invention have been described and their operation recited, except for minor details which are common knowledge and immediately obvious to those skilled in the art and which are directly apparent from the disclosure.

15 Although a preferred embodiment of my invention is illustrated in detail, it is obvious that changes and modifications may be made therein without departing from the spirit and scope of my invention, as defined 20 by the appended claim.

What is claimed is:

An X-ray device comprising an evacuated envelope, a target and a thermionic cathode therein, leading-in conductors for said cathode, and a focussing device for said cathode insulatingly supported by said leading-in conductors.

In testimony whereof, I have hereunto subscribed my name this 31st day of December 30 1923.

MONTFORD MORRISON.
